UNITED STATES PATENT OFFICE.

EDWARD JANSEN, OF NEW YORK, N. Y.

DESIGN FOR A FANCY BOX.

SPECIFICATION forming part of Design No. 23,330, dated June 5, 1894.

Application filed April 28, 1894. Serial No. 509,401. Term of patent 3½ years.

To all whom it may concern:

Be it known that I, EDWARD JANSEN, a citizen of the United States, and a resident of the city of New York, in the county of New York and State of New York, have invented a new and original Design for Fancy Boxes, of which the following is a specification.

In the accompanying drawing, a perspective view of a box covering embodying my new design is shown.

The leading feature of my design consists in a box provided with a covering composed of series of flat cords or narrow bands looped in the manner of knitting and interlooped with a smaller round cord, the flat and round cords forming fanciful figures which interlooped cords are placed on the faces of the box and cover.

In the drawing A are the flat cords or narrow bands, which are looped in the manner of a loose knitting with a large open mesh, and B are the round cords which are interlooped with the flat cords in the manner of loose knitting with a large open mesh.

Having thus described my invention, I claim as new and desire to secure by Letters Patent—

The design for fancy-boxes, as shown and described.

In testimony that I claim the foregoing as my invention I have signed my name in presence of two subscribing witnesses.

EDWARD JANSEN.

Witnesses:

OSCAR F. GUNZ,
K. R. BRENNAN.
